UNITED STATES PATENT OFFICE.

EDWARD BOURBEAU, OF MINNEAPOLIS, MINNESOTA.

FURNACE WALL.

Application filed January 23, 1925. Serial No. 5,369.

To all whom it may concern:

Be it known that I, EDWARD BOURBEAU, a citizen of the United States, residing at Minneapolis, in the county of Hennepin and State of Minnesota, have invented certain new and useful Improvements in Furnace Walls, of which the following is a specification.

This invention relates to furnace walls and the main object is to provide a composite wall consisting of a permanent masonry outer wall and a highly refractory re-placeable inner wall, and means of a novel and practical nature for anchoring the two walls together in a composite structure, whereby the inner wall may be firmly secured in place and readily replaced when damaged or burned out by the effect of high temperatures which are created in furnaces using walls of this type. Further and more specific objects will be disclosed in the course of the following specifications, references being had to the accompanying drawing, in which:

25 Figure 1 is a perspective view of a wall embodying my invention, said wall being only partly built up so as to illustrate its entire construction.

Figure 2 is a perspective view of one of 30 the lock head blocks forming a part of the outer wall structure.

Figure 3 is a detail sectional view through the wall as seen substantially on the line 3—3 in Figure 1.

35 Figure 4 is a longitudinal sectional elevation through two of the lock head blocks, about as on the line 4—4 in Figure 1.

Figure 5 is a detail perspective view of 40 one of the lintel plates used in the outer wall.

Figure 6 is a detail plan view showing a modification of my invention whereby it may be applied to an inside wall of a furnace, which is subjected to intensive heat 45 from both sides and therefore required a replaceable wall on each side of the permanent wall.

Referring to the drawing more particularly and by reference characters 7 designates a substructure of tile or brick which serves as a foundation for and carries the main wall proper. The so-called outer or permanent wall consists of horizontal series of lock head blocks A, pintel plates or tiles 55 B, and various intermediate or filler blocks

or tiles C, which combine with the blocks A and B to form the outer wall into a solid composite structure except for certain anchorage pockets (later to be described) in which certain members of the inner wall 60 are anchored. The blocks A are securely connected, at their adjoining ends, by lugs 8, at one end of each block, which lock into correspondingly shaped recesses 9, at the opposite ends of the blocks, and each lug 8 65 has a depending flange or bead 10, which seats, vertically in a corresponding groove 11 formed in the receiving recess 9 by an integral sill member 12 of the block, thus rigidly connecting the blocks and securing 70 them against transverse or longitudinal play or movement with respect to each other.

The inner or replaceable wall, which is exposed to the intense heat of the furnace, is composed of highly refractory groups of 75 tiles 13, 14 and D—E—F. The tiles 13 are laid in horizontal rows, and are connected at intervals by the short columns of tile 14 which are preferably crossed, as shown. The intermediate openings formed by the 80 tiles 13 and 14 are filled or occupied by the anchor blocks D—E—F, which tie the inner and outer walls together. These anchor blocks project with their lock ends into pockets 15 formed on the blocks A and are 85 supported on base portions 16 of the blocks, at one end, and upon the tiles 13 at the other end. The blocks E are straight at both ends, but the blocks or tiles D and F are provided at their inner ends with laterally projecting 90 ribs 17 which lock into corresponding vertical recesses 18 in the pockets 15. Thus the blocks E act as key blocks to lock the blocks D and F rigidly in place, and the latter blocks can obviously not be removed until 95 the key blocks E have first been removed.

The pintel plates B are provided in their under surfaces with wedge shaped openings 19, directly over the blocks D—E—F, so that the key block E may be pried up (see 100 Figure 3) and loosened so as to be readily removed. In the event that there should be any great resistance to the withdrawal of the block E it may be forced out by a rod or pin inserted in a hole 20, back of the 105 block, so that it may be forced out. After the block E has been removed, the adjoining blocks F and D can also, of course, be easily removed and replaced.

In the partition wall, shown in Figure 6, 110

the general construction and application of the invention is the same as shown in Figure 1, except that two outer replaceable walls G and H are built up and anchored to 5 the central wall I. The permanent wall I corresponds to the outer wall, in Figure 1, and the lock head blocks A¹ are provided with pockets on both sides for the reception of the anchor blocks D—E—F of both re- 10 placeable walls G and H.

It is understood that various modifications may be made in the general details of the invention as herein illustrated and described, providing, however, that such 15 modifications come within the spirit and scope of the appended claims. Having now therefore, fully shown and described my invention, what I claim to be new and desire to protect by Letters Patent is:—

20 1. A wall structure having a permanent wall and a replaceable wall, said outer wall including a horizontal series of adjoining interlocked lock head blocks, a pair of anchor tiles extending into each lock head 25 block from the other wall and forming a part of said other wall, and a removable key tile arranged between said anchor tiles of each pair to lock them rigidly with respect to the lock head blocks into which 30 they extend.

2. A wall structure comprising a permanent wall having anchorage pockets therein, and a replaceable wall having anchor tiles projecting therefrom and into said 35 pockets, said anchorage tiles having lateral projections for locking engagement in said pockets, a key tile adapted to be inserted between two of said anchor tiles to hold them in locked positions, the portion of the 40 outer wall immediately above said key tile having a recess whereby the key tile may be

pried up to loosen it from its normal locking position.

3. A wall structure comprising a permanent wall and a replaceable wall, said permanent wall having horizontal rows of adjoining blocks having pockets with lateral recesses, said replaceable wall having pairs of anchor tiles extending into said pockets, each of said tiles having ribs for engagement in said recesses, and a key tile inserted between the anchor tiles of each pair for securing such anchor tiles in locked positions in said pockets. 45 50

4. A wall structure having a permanent outer wall and a replaceable wall, said outer wall comprising a series of lock head blocks having pockets, anchor blocks secured in said pockets and extending into the replaceable wall, each of said lock head blocks having a lug in one end and a recess in the other end for receiving the lug of the adjacent lock head block whereby the lock head blocks may be identically formed and locked together. 55 60 65

5. A wall structure having a permanent outer wall and a replaceable wall, said outer wall comprising a series of lock head blocks having pockets, anchor blocks secured in said pockets and extending into the replaceable wall, each of said lock head blocks having a lug in one end and a recess in the other end for receiving the lug of the adjacent lock head block, the lug of each block having a projecting flange, and the recess of each block having a flange receiving groove, whereby the blocks may be interlocked end to end and to prevent spreading of the blocks from each other. 70 75

In testimony whereof I affix my signature. 80

EDWARD BOURBEAU.
